SUPERCHARGER MECHANISM FOR INTERNAL COMBUSTION ENGINES

Original Filed March 17, 1933

UNITED STATES PATENT OFFICE

2,098,718

SUPERCHARGER MECHANISM FOR INTERNAL COMBUSTION ENGINES

Harold Caminez and Norman H. Gilman, Indianapolis, Ind., assignors to General Motors Corporation, Detroit, Mich., a corporation of Delaware

Original application March 17, 1933, Serial No. 661,327. Divided and this application May 20, 1936, Serial No. 80,734

6 Claims. (Cl. 123—59)

Our invention relates to multiple cylinder internal combustion engines designed, particularly, for dirigible balloon, airplane and like aeronautical service; and particularly to engines of the V type, having two cylinder blocks arranged at an angle to one another and each block having a plurality of parallel cylinders. In the embodiment of our invention illustrated and hereinafter described twelve cylinders are present in two blocks arranged at an angle of 60 degrees to one another.

This present invention has to do with supercharging mechanism for increasing the volume of air or combustible mixture supplied to the cylinders of the engine, and includes driving means for the usual centrifugal pump which forms a part of such mechanisms; and the drawing accompanying and forming a part of this specification illustrates only such parts and features of the engine as are necessary to an understanding of this present invention.

In the drawing wherein the preferred form of our invention is illustrated:

Figure 1 is a view showing a section upon vertical central planes indicated by the broken line 1—1 of the schematic plan view, Figure 2.

Figure 2 is a schematic view showing the engine, or so much of it as is necessary to an understanding of this present invention, in plan.

Figure 3 is a view showing certain joint and flame stop features of our invention.

Referring now to the drawing, the numeral 5 designates the upper and 6 the lower of two castings which together form a crank case for the engine, the two meeting in the plane of the crank shaft the front end only of which is shown. The crank case parts meet in the plane of the crank shaft and are secured together by bolts extending through flanges as shown, and the 10 main journals thereof (seven in the engine illustrated) are supported in bearings held in semi-circular seats provided in transverse webs in the two parts of the case, as is usual in multiple cylinder engines. Only one such web, journal, and 15 bearing is shown, the same being the front end journal 7 and the bearing 8 therefor. The upper half 5 of the crank case supports the cylinder blocks the farther block 9 being shown in elevation, and somewhat conventionally; whereas 20 the nearer of the two blocks is omitted.

The front end of the crank shaft has a pinion 9' which meshes with an internal gear 10 carried by a flange 11 which drives a propeller, not shown. The periphery of this gear is cylindrical in form and rotates in a bearing 12 likewise held

in semi-circular seats in the crank case whereby support is provided as close as possible to the internal teeth of the gear 10; and this gear 10 carries an external gear 13 which meshes with a pinion 14, which is formed integrally with short hollow journals 15, 16 supported in bearings 17, 18 within and at the front end of the crank case member 5. The journal 16 has internal splines which cooperate with splines upon the end of a shaft 19 to drive the same and the rear end of 10 which is hollow and is provided with internal splines, and is supported in a bearing 20 within and at the rear end of the upper half 5 of the crank case. The shaft 19 therefore and as will be seen extends along the crank case and is located 15 within and close beneath the top wall thereof. An intermediate bearing 21 is also shown for steadyng the central part of the shaft 19 because of its considerable length.

The right hand or rear end of the crank case 20 sections 5, 6 lie in a single vertical plane, and secured to said sections through suitable flanges and bolts is an accessory housing 56 which has built thereto the centrifugal compressor or supercharger whereby mixture is supplied to the 25 engine cylinders under pressure greater than atmospheric pressure; and which accessory housing serves also to support various engine accessory devices such as the carburetor, the ignition magneto, the generator for the starting motor, the 30 starting motor itself, the oil and fuel pumps, the pump for the cooling liquid and other accessories, as well also as the immediate driving means for such accessories; the housing and accessories assembled therewith thus forming a single assembly 35 independent of the crank case and cylinder blocks. Inasmuch, however, as this present application has to do with supercharging mechanism for the engine only such features of the accessory housing as have to do with such mechanism are shown in detail.

The accessory housing is bolted to the crank case along a plane indicated by the numeral 22; and 23 is a compressor rear wall and bearing carrying plate secured against a circular seat 24 in 45 the housing and shaped to form the left hand wall of the air compressor, and which plate supports bearings for the driving mechanism of the rotating impeller 25 of the compressor. This impeller is carried by a shaft 26 rotatable in bearings 27, 28 carried by the plate 23 and which bearings, as will be seen, are located inside the housing 56; and between these bearings is a pinion 29 which is driven by a gear 30 upon a shaft 31. The right hand end of this short shaft 31 is 55

supported in a bearing 32 carried by the plate 23, and the left hand thereof is splined and enters into the splined end of the shaft 19; so that the compressor rotor 25 is driven from said shaft 5 19 through the gear 30 and pinion 29.

The outer front wall or plate 33 of the compressor is secured in place in a circular seat 34 concentric with the seat 24 and formed in the outer wall of the housing, and this outer wall has 10 an inlet elbow 35 formed integrally therewith and which is shown as communicating with a down draft carburetor 36 of any suitable form. The plates 23 and 33 are so shaped as to provide 15 a chamber for the impeller 25 and a restricted passage 37 between them which passage is comparatively narrow, but of considerable length, radially, and through which the air flows from the impeller chamber into a comparatively large 20 annular chamber 38 surrounding the outlet from the passage 37 and merging into a large upper discharge elbow 39; both the chamber 38 and the elbow being parts of the housing 56 and the whole 25 being secured to and supported from the rear end of the crank case 5, 6 as hereinbefore explained.

The plates 23 and 33 form an air passage from the carburetor 36 to the elbow 39, and they are secured in seats in and form a part of the accessory housing which housing, however, is not disclosed in detail as this present invention does not relate particularly thereto. The restricted passage 37 between the high pressure discharge of the compressor and the comparatively large space provided by the air chamber 38 and elbow 39 30 provides a construction which equalizes the discharge from the compressor, and in which surges of air are avoided and a more uniform pressure in the chamber 38 and flow of mixture therefrom and throughout the supply manifold system and 35 to the engine cylinders is secured, than in mixture supply systems heretofore in use.

Arranged in the inlet passage leading from the carburetor to the air compressor 25, and located as close as possible to the inlet thereof, is a stationary vane member comprising a central cone-shaped hub 40 and a series of radial vanes 41 extending therefrom to a peripheral ring 42, which is seated in a recess provided in the outer wall or plate 33.

50 The stream of combustible mixture which flows through the elbow 39 is divided into two parts by a hollow connector 43 arranged adjacent the rear end of the engine, one part thereof flowing onward and upward through a short passage or conduit and into a transverse conduit 44 wherein it is divided again, half going to the three rear cylinders of the farther block and half to the three rear cylinders of the nearer block. The second part of the mixture flows onward 55 from the connector 43 through a conduit 45 and upward into a second transverse conduit 46 wherein it is likewise again divided, half going to the three front cylinders of the farther block and half to the three front cylinders of the nearer block. 60

The transverse conduit 44 leads into headers 47, 48 each of which is a hollow cast metal structure secured to a cylinder head common to all the cylinders of a block, and the interior of 65 which communicates with the inlet passages leading into said cylinders. Said two headers, therefore, supply combustible mixture to the six rear cylinders of the engine, each header supplying three cylinders of an engine block.

70 The conduit 46 leads into headers 49, 50 for

the six forward cylinders which headers are identical with those above described, and act in the same way to supply mixture to said forward cylinders; from which it follows that each group of three cylinders derives its supply from one single header, and that the supply to each group of three is isolated from that of other groups, thus securing a more uniform distribution of the mixture to the cylinders than would be the case were a larger number than three to derive their supply from a single header or like immediate source. Variations in suction in any particular header due to the cylinders which it supplies not being identical with other groups of cylinders, or due to temporary irregularities of operation 10 of such cylinders, or to other causes, will therefore not be communicated to other headers or if communicated will be communicated to but a slight extent. Irregularities of operation of one of the three cylinders which any particular header supplies will to be sure affect the operation of the other two, but the effect of any such irregularity will be limited mostly, and indeed substantially entirely, to the three cylinders supplied by the header in question. 15

The entire supply manifold system is located in the V-shaped space between the cylinder blocks, and its construction is obviously such that the flow of the mixture is uniformly upward and toward the engine heads, the one of the farther 20 block being indicated by the numeral 51. The manifold system is provided with expansion joints at various places where parts thereof are joined together, one of such joints being shown in section in Figure 3; and back-fire preventing screens 25 52 of any suitable type are secured in place at these joints as shown in said figure. In the form of our invention illustrated such flame stops are contemplated also at the joints 53 and 54, their purpose being to prevent the ignition of the mixture in the compressor and carburetor should the mixture in the headers, as is often the case, be ignited by backfires from the engine cylinders. 30

The numeral 57 designates a heating jacket 35 arranged between the carburetor 36 and the inlet into the mixture compressor for heating the combustible mixture, and through which hot liquid taken from the cooling system of the engine is caused to flow by the use of suitable 40 pipes not shown. 45

The shaft 19, as will be appreciated, is comparatively long, and its diameter is preferably reduced intermediate its ends as shown. This feature of a long and slender driving shaft provides torsional flexibility in the driving mechanism for the impeller of the centrifugal compressor, and very materially reduces the transmission of torsional vibrations commonly present in crank shafts of multiple cylinder engines to the rotating impeller of the centrifugal compressor, which is ordinarily driven at a speed considerably above that of the crank shaft and should be driven at a uniform speed. The torsional resiliency inherent in the long and slender driving shaft for the impeller secures the driving thereof without shocks, and a smoother running 55 impeller than would otherwise be the case. 60

This present application is a division of our application for patent for Intake manifold system for internal combustion engines, Serial Number 661,327, filed March 17, 1933, which parent application relates to manifold features, whereas this present application relates to supercharging mechanism and driving means therefor, for supplying said manifold system. 70 75

Having thus described and explained our invention we claim and desire to secure by Letters Patent:

1. In supercharging mechanism for multiple cylinder internal combustion engines, a housing separate from the crank case of the engine and secured to the rear end thereof; a centrifugal compressor associated with said housing and the shaft of the impeller of which is rotatable in a bearing device located within said housing, said compressor having an inlet leading thereto, and an outlet which communicates with a conduit system whereby combustible mixture is supplied to the cylinders of the engine; a shaft extending longitudinally of the engine and throughout the length of the crank case thereof, and which shaft is rotatably supported in bearings at the ends of said crank case; gearing at the front end of the crank case for driving said shaft; and means whereby the impeller shaft of said compressor is driven from the rear end of said longitudinally extending shaft.

2. In supercharging mechanism for multiple cylinder internal combustion engines, a housing separate from the crank case of the engine and secured to the rear end thereof; a centrifugal compressor associated with said housing and the shaft of the impeller of which is rotatable in a bearing device located within said housing, said compressor having an inlet leading thereto, and an outlet which communicates with a conduit system whereby combustible mixture is supplied to the cylinders of the engine; a shaft extending longitudinally of the engine and throughout the length of the crank case thereof, and which shaft is rotatably supported in bearings at the ends of said crank case; gearing at the front end of the crank case for driving said shaft; a short shaft with which the rear end of said longitudinally extending shaft is operatively connected; a bearing within said housing and whereby the extremity of said short shaft is supported; and gearing whereby and through which the impeller shaft of said compressor is driven by said short shaft.

3. In supercharging mechanism for multiple cylinder internal combustion engines, a housing separate from the crank case of the engine and secured to the rear end thereof; a centrifugal compressor associated with said housing and the shaft of the impeller of which is rotatable in bearings within said housing, said compressor having an inlet leading thereto, and an outlet which communicates with a conduit system whereby combustible mixture is supplied to the cylinders of the engine; a shaft extending longitudinally of the engine and throughout the length of the crank case thereof, and which shaft is rotatably supported in bearings at the ends of said crank case; gearing at the front end of the crank case for driving said shaft; a short shaft arranged in line with said longitudinally extending shaft, and means for providing a splined driving connection between said two shafts; a bearing within said housing and whereby the extremity of said short shaft is supported; a gear carried by said short shaft; and a pinion

upon the impeller shaft of the compressor with which said gear meshes to thereby drive said impeller.

4. In supercharging mechanism for multiple cylinder internal combustion engines, a housing 5 separate from the crank case of the engine and secured to the rear end thereof; a compressor rear wall secured in a seat provided in said housing, and having two bearings spaced apart from one another for supporting the shaft of a centrifugal compressor; a compressor front wall secured in a seat provided in said housing and having an inlet, said walls being shaped to provide an impeller chamber and a narrow passage leading therefrom into an enlarged annular 10 chamber surrounding the outlet from said narrow passage; a discharge member associated with said housing and through which mixture flows from said annular chamber; a rotary impeller within said impeller chamber and the shaft of 15 which is supported in the bearings aforesaid; and means for driving said impeller shaft from the front end of the engine.

5. In supercharging mechanism for multiple cylinder internal combustion engines, a housing 25 separate from the crank case of the engine and secured to the rear end thereof; a compressor rear wall secured in a seat provided in said housing, and having two bearings spaced apart from one another for supporting the shaft of a centrifugal compressor; a compressor front wall secured in a seat provided in said housing and having an inlet, said walls being shaped to provide an impeller chamber and a narrow passage 30 leading therefrom into an enlarged annular chamber surrounding the outlet from said narrow passage; a discharge member associated with said housing and through which mixture flows from said annular chamber; a rotary impeller within said impeller chamber and the shaft of 35 which is supported in the bearings aforesaid; a short shaft the extremity of which is supported in a bearing carried by said compressor rear wall; intermeshing gears whereby said short shaft drives said impeller shaft; and a driving shaft 40 extending from the front end of the engine through the crank case thereof and the rear end of which is operatively connected with said short shaft.

6. In supercharging mechanism for internal 50 combustion engines having two cylinder blocks arranged at an angle to one another and each having a plurality of cylinders, and which system is arranged within the space between said cylinder blocks and communicates with all of said 55 cylinders so as to supply combustible mixture to all of them; a centrifugal compressor arranged at one end of said blocks whereby combustible mixture is supplied to said system; gearing driven by the crank shaft of the engine arranged at the other end of said blocks; and a long slender shaft driven by said gearing and adapted to drive the impeller of said compressor, whereby torsional vibrations of said crank shaft are absorbed by said long shaft.
